UNITED STATES PATENT OFFICE.

CHARLES H. OCUMPAUGH, OF ROCHESTER, NEW YORK.

SASH-BALANCE.

SPECIFICATION forming part of Letters Patent No. 596,216, dated December 28, 1897.

Application filed November 14, 1896. Serial No. 612,121. (No model.)

To all whom it may concern:

Be it known that I, CHARLES H. OCUMPAUGH, of Rochester, in the county of Monroe and State of New York, have invented a certain new and useful Improvement in Sash-Balances; and I do hereby declare that the following is a full, clear, and exact description of the same, reference being had to the drawings accompanying this application.

10 My improvement relates to that class of spring-balances in which the tape or cord that holds the sash winds on a spring-actuated drum.

The invention consists in the construction 15 and arrangement of parts hereinafter described, and embodied in the claims.

In the drawings, Figure 1 is a longitudinal vertical section of the device. Fig. 2 is a vertical cross-section of the same in line $x-x$ of 20 Fig. 1. Figs. 3, 4, 5, and 6 are perspective views of the several parts of the device separated.

The invention consists more especially in 25 the construction of the casing and the pintle on which the spring-actuated drum turns.

The casing is composed of two parts A and B, each made in a single piece of cast metal. The first part A forms what I denominate the "cover-plate," and consists of a face-plate a , 30 provided with the usual cord-slot a' , a side plate a^2 , and two inwardly-projecting lugs $a^3 a^3$. It also has a rivet-hole a^4 . The plate A, which covers the hood B and together with it constitutes a complete close inclosing case 35 entirely separate from the drum, is so made that it can be cast complete and ready for use, except that it must subsequently be provided with the hole a^4 . This result is secured by the particular arrangement of the 40 side plate A² with respect to the face-plate and the openings therein, whereby the cover-plate, consisting of the integral face and side plates, can be drawn after casting. This is a result of practical value not before attained 45 and impossible in any prior construction. The cover-plate A and hood B are positively fastened together by the rivet d , and no other fastening is required. Lugs a^3 serve to merely determine and maintain the relative situation 50 of the cover-plate and hood in direction parallel to the face-plate, and means acting substantially like these lugs are deemed impor-

tant, but it is not necessary to employ any fastening between the parts except the rivet d . The second part B forms what I denominate the "hood," and consists of a side plate b , a circular segmental ring b' , and a projecting hollow pintle b^2 , provided with an interior shoulder b^3 , a rivet-hole being made through the shoulder and the side plate to receive the 60 rivet. These two parts when fitted together form an inclosure in which is located the spring-actuated drum D, the latter being covered entirely from sight by the inclosing rim b' of the hood. The edges of the rim simply 65 fit loosely over the lugs $a^3 a^3$, but are not attached thereto, the parts being held together by the central rivet hereinafter described.

On the inner face of the spring-actuated drum D is a hollow pin c , which enters the 70 pintle b^2 , its end striking the shoulder b^3 , as shown in Fig. 2. Through the hole in the pin c and through corresponding holes in the two sides of the case is passed a rivet d , which, after being inserted, is riveted down at both 75 ends, thus securing the two parts A and B of the case together and inclosing the drum. Any desired degree of friction between the drum and plates a^2 and b' of the parts A B can be secured by varying the tightness of the 80 rivet. The rivet, however, does not bear laterally on the spindle c of the drum. Said spindle has instead an exterior bearing in the spindle b^2 , whereby it is securely held, said latter spindle being fast to the part B, which 85 is held solidly against the flanges $a^3 a^3$ and part A by the rivet, this being the sole function of the rivet, except as it incidentally affects the tension on the drum by drawing said parts A and B toward each other and against 90 the drum more or less closely. Heretofore a screw situated within a drum-spindle has been relied upon to furnish a bearing for the drum. Such screw is liable to be turned by the drum, and thus interfere with the tension of the 95 drum-spring. In such prior construction a second spring was relied upon to produce tension between the casing and drum. By the present improvement this spring is dispensed with and the rivet and casing produce the 100 tension, as stated. In the hollow face of the drum is the ordinary coiled spring E, the inner end being fastened to the pintle b^2 of the hood, and thus held stationary. The other

or outer end of the spring is fastened to the rim of the drum. The spring is put under tension by uncoiling it. It therefore avoids all friction of parts of the spring upon themselves when put under tension and the consequent strain upon the spring-fastening.

A³ A³ are two lugs cast on the outer side of the face-plate A on each side of the opening a'. The object of these lugs is to enable the 10 spring-drum to be located farther forward, thus economizing space and reducing the size of the balance. The spring-drum being set farther forward, the tape may be wound on its exterior in quantity to extend through the 15 face-plate adjacent said lugs or flanges a³, which in such case protect and guide the tape which may be drawn down parallel with the face-plate and without being drawn across the bottom of the tape-slot. It also enables 20 a greater length of tape to be coiled on the drum without increasing the depth of the mortise.

It may be noted that the rivet d fastens all the parts together in operative relation with- 25 out the necessity of using any other rivets or separable fastening devices. The rivet is also used in combination with the pintles to properly adjust or brake the spring-drum. This has heretofore been effected by the medium 30 of the periphery of the drum or by a flange on such periphery; but such constructions either involve a separate or expensive braking device, or if a flange on the drum bearing on the case is relied upon it is too noisy 35 and the said braking-flange has made necessary an enlargement of the case. These objections are avoided by pintles constructed as herein shown and described, one of them

having an interior shoulder to act as a bearing for the end of the other and coöoperating 40 with the rivet to furnish a brake for the drum.

This device is practically noiseless in operation, requiring no enlargement of the case, and is simpler and cheaper to manufacture.

Having described my invention, I claim— 45

1. In a sash-balance the combination of the cover-plate A comprising a face-plate a and a side plate a² integral therewith, and lugs a³, a³, also integral with the face-plate, each of said lugs being situated in the angle between the face-plate a and the side plate and near the edge of the latter, a hood B having a side plate b and integral therewith a rim b' said rim abutting against the face-plate adjacent the lugs and also against the side plate 55 adjacent its edge and having a hollow pintle b² constituting a bearing for a drum D said drum situated within the casing formed by said cover-plate side plate and face-plate, the drum having a hollow pintle c fitting the hollow pintle b², and a rivet d uniting the main parts of the casing, substantially as described. 60

2. The combination of the face-plate a integral with the side plate a², the hood B provided with a spindle b² having a shoulder, 65 with the drum having a spindle c bearing against the shoulder in said spindle b² to constitute a brake, substantially as described.

In witness whereof I have hereunto signed my name in the presence of two subscribing 70 witnesses.

CHARLES H. OCUMPAUGH.
